DESIGN FOR AN ASH TRAY

Max Millman, Providence, R. I.

Application October 24, 1945, Serial No. 123,144

Term of patent 3½ years

(Cl. D85—2)

To all whom it may concern:

Be it known that I, Max Millman, a citizen of the United States, residing at Providence, in the county of Providence and State of Rhode Island, have invented a new, original, and ornamental Design for an Ash Tray, of which the following is a specification, reference being had to the accompanying drawing, constituting a part thereof.

Fig. 1 is a perspective view of an ash tray showing my new design; and

Fig. 2 is a top plan view thereof.

I claim:

The ornamental design for an ash tray, substantially as shown.

MAX MILLMAN.
